C. Snow & Co.

UNITED STATES PATENT OFFICE.

JOSEPH A. KLOEB, OF WASHINGTON, DISTRICT OF COLUMBIA, ASSIGNOR
OF ONE-HALF TO CARL J. MESS, OF SAME PLACE.

GAS-BURNER.

SPECIFICATION forming part of Letters Patent No. 591,046, dated October 5, 1897.

Application filed February 20, 1897. Serial No. 624,297. (No model.)

To all whom it may concern:

Be it known that I, JOSEPH A. KLOEB, a citizen of the United States, residing at Washington, in the District of Columbia, have invented a new and useful Gas-Burner, of which the following is a specification.

My invention relates to gas-burners particularly adapted for use in connection with heating and analogous devices; and the object in view is to provide a construction and arrangement of parts whereby with a single burner the desired amount of heat may be produced by the use of an orifice (for introducing the gas into the mixer) which is sufficiently diminutive in size to prevent back pressure.

It has been the practice heretofore to increase the size or diameter of the orifice through which the gas is supplied in order to increase the heat produced by the burner, the amount of heat being proportionate to the amount of gas consumed, but an efficient orifice must be of such a size as to produce a partial vacuum in the mixer in order to induce the necessary amount of air, it being obvious that the efficiency of the burner depends greatly upon the intimate mixture of the gas with a sufficient quantity of air to contain the necessary amount of oxygen. Hence when the orifice is increased beyond a certain diameter the pressure under which the gas is discharged into the mixer is diminished, (assuming that the fuel is supplied at a uniform pressure,) and hence the induction of air is reduced and the efficiency of the burner is proportionately diminished. In addition to this disadvantage of increasing the diameter of the orifice through which the gas is supplied to the mixer, back pressure is liable to ensue, thereby still further interfering with the operation of the device.

In order to overcome the above disadvantages, the expedient of multiplying the number of burners has been tried, but aside from the item of expense incident to this plan it frequently happens that there is only sufficient space in the furnace or article to be heated for a single burner of the standard size, and therefore the only alternative is to increase the flow of gas by magnifying the size of the orifice, with the resulting disad-

vantages above named. In order to overcome these disadvantages, I have devised a construction of burner adapted to be used in place of the ordinary or standard size burners now in common use, said improved burner having a capacity which is a multiple of that of the ordinary forms of burners, but wherein the orifice through which gas is discharged into the mixer may be as small as desired. In other words, I have devised a construction of burner whereby the amount of gas consumed may be varied or multiplied to the desired extent without the disadvantages incident to increasing the size of the opening through which the gas is supplied.

A further object of my invention is to provide members of interchangeable construction whereby the mixer may be changed to suit the requirements of the burner, different mixer attachments being provided with orifices varying in area.

Further objects and advantages of this invention will appear in the following description, and the novel features thereof will be particularly pointed out in the appended claims.

In the drawings, Figure 1 is a side view of a burner constructed in accordance with my invention. Fig. 2 is a vertical sectional view of the same, taken in the plane of and axially through two tubes which form members of the mixer. Fig. 3 is a vertical central section of the burner-cap and contiguous portion of the mixer to show the disk-valve in operative relation with the air-inlet openings of the burner-cap. Fig. 4 is a horizontal section of the mixer-tubes in the plane of the means whereby the air-inlet openings thereof are controlled to vary the influx of air. Fig. 5 is an inverted plan view of the disk-valve whereby the air-inlet openings of the burner-cap are controlled. Fig. 6 is an inverted plan view of the burner-cap detached.

Similar numerals of reference indicate corresponding parts in all the figures of the drawings.

In the construction illustrated in the drawings the receiver or fuel-chamber 1 is adapted to be of a size suitable for direct attachment to a common or standard size of gas-supply conveyer 2, said receiver being fitted with a

removable head 3, carrying a mixer which consists of a plurality of mixer-tubes 4, the head 3 being detachable from the receiver in order to facilitate the replacement of the 5 mixer by others varying therefrom in the diameter of their mixer-tubes.

Fitted in the lower ends of the mixer-tubes are throttling-blocks 5, having gas-supply orifices 6 of such diameter as to prevent back 10 pressure from the mixer and cause the gas to be discharged from the receiver into the mixer-tubes with such force as to produce an efficient partial vacuum contiguous to the air-inlet openings 7 in said tubes, these air-inlet 15 openings being controlled by annular slides 8, fitted for vertical movement upon the tubes and adapted to be adjusted to expose the desired portions of the areas of the openings. Said slides are also provided with securing 20 devices, such as set-screws 9, adapted to impinge against the exterior surfaces of the tubes to lock the slides at the desired adjustment.

The mixer-tubes communicate at their upper 25 ends with a burner-cap 10 of any desired construction, preferably trunco-conical with a serrated terminal edge, the connection between the cap and the mixer-tubes being by means of a "slip-joint," consisting of smooth 30 openings in the floor of the burner-cap, loosely fitted upon slightly-tapered portions of the mixer-tubes and adapted to be unseated or detached by an upward movement of the cap.

In the floor of the burner-cap are formed 35 air-inlet openings 11, any desired number of which may be employed, and fitted to slide upon the mixer-tubes below the plane of the bottom of the cap is a disk-valve 12, coextensive with the bottom of the cap and adapted 40 when arranged in contact with the latter to entirely close the openings 11 and exclude air at that point. When it is desired to supply oxygen to the flame at the base of the burner-cap, this disk is adjusted downwardly 45 to form a slight space between its upper surface and the bottom of the cap, and thus expose the openings 11, and by varying the vertical position of the disk more or less air may be admitted to the burner-cap.

50 Any suitable means may be employed for securing the disk at the desired adjustment, such as the set-screws 13, shown on the depending collars 14, which slide upon the mixer-tubes.

55 From the above description it will be seen that by using an orifice 6 which is sufficiently small to avoid the disadvantages hereinbefore described as incident to an enlarged orifice the amount of fuel supplied to the burner 60 may be varied to produce the desired amount of heat, and at the same time an economical consumption of the fuel is insured by the fact that each member or tube of the mixer is exposed at all sides and is provided with 65 an annular series of air-inlet openings, whereby the admixture of air is complete and efficient. In other words, while the mixer com-

prises a plurality of members and is thus increased in the matter of the heat produced in accordance with the number of members, 70 each mixer operates independently of the others and is as fully efficient as could be a single mixer, as in the ordinary practice, without any of the disadvantages due to an incomplete commingling of combustion-sup- 75 porting agent with the fuel. Thus I have provided a plurality of mixer-tubes in communication with a common gas-receiver which is adapted to be connected with an ordinary gas-supply pipe to replace a single 80 burner or a single-mixer burner of the ordinary construction, and the mixer-tubes are so arranged in contiguity that the flames proceeding therefrom are combined to form a single flame, this combination being facilitated by the cap 10 when the latter is employed in connection with the mixer-tubes. The mixer-tubes are preferably arranged in an annular series around a common center 85 to provide for the plural-mixer burner con- 90 stituting my invention, being arranged practically in the space ordinarily occupied by a single-mixer burner. This is made possible by the fact that the cross-sectional areas of the mixer-tubes need not be individually extensive, especially when the gas-orifices are made of a diameter not exceeding three thirty- 95 seconds of an inch, this being the maximum efficient size.

The removability of the head of the receiver 100 materially facilitates the replacement and interchanging of throttling-plugs which are removably fitted in the lower ends of the mixer-tubes, the drawings showing these plugs screw-threaded into said tubes. 105

Various changes in the form, proportion, and the minor details of construction may be resorted to without departing from the spirit or sacrificing any of the advantages of this 110 invention.

Having described my invention, what I claim is—

1. A gas-burner having a plurality of mixer-tubes provided with independent gas-inlet orifices and contiguous to each other, and 115 equidistant from a common point, openings for the admission of a combustion-supporting agent, said tubes being contiguous to combine the flames issuing therefrom, and a common burner-cap 10 into which the flames issuing from the several tubes are discharged, the same being removably fitted upon and supported by the tubes, substantially as specified.

2. A gas-burner having a receiver provided 125 with a removable head, a plurality of mixer-tubes supported by the said head and arranged contiguous to each other to combine their flames, and plugs having gas-inlet orifices removably fitted in the lower ends of the 130 tubes, said tubes being provided with lateral air-inlet openings, substantially as specified.

3. The herein-described gas-burner comprising a plurality of contiguous mixer-tubes

communicating through reduced gas-inlet ori-
fices with a common receiver, and each pro-
vided with lateral air-inlet openings, con-
trolling devices for varying the areas of said
5 air-inlet openings, a common cap for the
mixer-tubes whereby the flames discharged
therefrom are combined, said cap having
openings in its floor to receive the mixer-
tubes and being contracted toward its open-
10 outer end, and also having its floor extended
beyond the remote sides of the mixer-tubes
and provided with air-inlet openings, a disk-
valve coextensive with the perforated floor
of the cap, and provided with a plurality of
15 openings and aligned collars, corresponding in
number with the mixer-tubes and fitted there-

on for sliding movement parallel therewith,
whereby the disk-valve may be adjusted to
vary the admission of air through the open-
ings in said floor of the cap, and set-screws 20
mounted upon the collars of the disk-valve
for impinging against the surfaces of the mix-
er-tubes to secure said valve at the desired
adjustment, substantially as specified.

In testimony that I claim the foregoing as 25
my own I have hereto affixed my signature in
the presence of two witnesses.

JOSEPH A. KLOEB.
